UNITED STATES PATENT OFFICE.

C. GEORGE ADAMEC, OF MILWAUKEE, WISCONSIN.

DESIGN FOR A TOY.

59,805.

Specification for Design.

Patented Nov. 29, 1921.

Application filed April 14, 1921. Serial No. 461,419. Term of patent 7 years.

To all whom it may concern:

Be it known that I, C. GEORGE ADAMEC, a citizen of the Czechoslovak Republic, residing at Milwaukee, in the county of Milwaukee and State of Wisconsin, have invented a new, original, and ornamental Design for a Toy, of which the following is a specification, reference being had to the accompanying drawing, forming part thereof.

Figure 1 is a front view of a toy showing my design, and

Fig. 2 is a rear view thereof.

I claim:

The ornamental design for a toy, as shown.

C. GEORGE ADAMEC.
